UNITED STATES PATENT OFFICE

PAMELA BULLOCK, OF COUNTY OF MIDDLESEX, ENGLAND; PERCY WILLIAM BULLOCK, EXECUTOR OF SAID PAMELA BULLOCK, DECEASED, ASSIGNOR TO PERCY WILLIAM BULLOCK, OF HENDON, MIDDLESEX, ENGLAND

SHOE, SLIPPER, BOOT, AND THE LIKE

Application filed January 19, 1928, Serial No. 247,973, and in Great Britain February 25, 1927. Renewed November 20, 1930.

This invention relates to shoes, slippers, boots and the like, e. g. goloshes, hereinafter referred to as shoes, of the kind wherein the upper opens at the back and the two sides of the back terminate in flaps which overlap each other, and has for its object an improved construction of the same so as to facilitate the introduction of the foot therein and the securing of such footwear on the foot.

According to my invention the upper is divided substantially down to the sole at or near the center of the counter and the parts of the upper at such division are extended on each side beyond the area of pressure between the heel of the foot and the counter of the shoe so as to overlap one another and to form a tag or finger piece on each side of the foot, whereby such extensions may be grasped and the overlapping parts drawn tight, means being provided for securing such overlapping parts and their extensions in position on the foot.

The outer overlapping part or extension of the upper is preferably made so as to taper into the form of a strap or straps, or is otherwise formed so as to be capable of being fastened by means of a strap or straps, means such as a buckle, clip or button being provided for securing such overlapping part or extension to the outside of the upper at the outer side of the shoe. The inner extension is arranged so as to wrap around the inside of the upper a convenient distance and may be either fastened or left unfastened as desired. In the case where it is fastened, the inner extension may be tapered into a strap, but it may with convenience be left unfastened and only slightly tapered, so that it and the outer extension can be utilized as tags to facilitate the insertion of the foot into the shoe.

By this means, the quick and easy insertion and withdrawal of the foot into and from the shoe is permitted, and no cramping of the toes and instep is required as heretofore to force the heel of the foot into a box formed by a stiffened closed heel of the type heretofore usual. When the foot is in position in the shoe, the overlapping parts or exten-

sions of the upper are wrapped around the heel of the foot and preferably the outer one is secured by the buckle or clip, as above mentioned.

In some cases, a loop may be provided through which the strap extends on the exterior of the shoe so as to retain the strap approximately in position when unfastened. Moreover the outer flap can be branched or forked at its free end, the branches or straps being secured by separate buckles or fasteners, or by means of one or more clips or fasteners, each adapted to engage two or more straps. Or both the inner and the outer overlapping extensions of the rear parts of the upper can be formed into straps which are secured either to one another or to the exterior of the upper. Furthermore, instead of the flaps just meeting one another at the place where they are attached to the sole, they may be secured to one another and/or to the sole for a short distance beyond the place of division.

In a further modification one or both of the rear parts of the sides of the upper is or are only secured to the sole substantially up to one end or the ends of the rear curve of the heel.

In order to enable the shoe to be used in cases where an exceptional amount of water is liable to be encountered there may be provided a heel closing piece formed of thin flexible and waterproof material secured at its bottom edge around the curve of the heel, it being also secured at one or both sides to the corresponding flap or flaps of the upper. In cases where this heel closing piece is secured to the interior of the upper on both sides, it may be provided with preferably vertical pleats at the sides so as to enable it to lie smoothly when the overlapping parts or extensions are wrapped around the heel in the closed or fastened position of the shoe.

Moreover in cases where such a closing piece is not employed, a strip or tongue of packing material can be arranged to lie between the overlapping parts or extensions of the upper, such packing strip being stitched or lasted into the sole and preferably secured to one of the overlapping parts or ex-

tensions in such a manner as to extend from the sole upwards.

In the accompanying drawings, I have shown how my said invention may be conveniently and advantageously carried into practice. In such drawings:—

Figure 1 is a perspective view of a left foot shoe having my invention applied thereto, shown in the open position.

Figure 2 is a similar view of the right foot shoe corresponding to that illustrated in Figure 1, but shown in the closed position.

Figures 3 and 4 are perspective views of right and left foot shoes shown respectively in the open and closed positions illustrating a modification.

Figures 5 and 6 are similar perspective views illustrating another form of my improved shoe.

Figures 7, 8 and 9 are perspective views showing further forms of my improved shoe.

Figure 10 shows a shoe the principles of the opening and the fastening of which may be used for a waterproof golosh.

Figures 11 and 12 are views showing further modifications in the open position.

Figures 13 and 14 show the application of my invention to a boot.

Referring to Figures 1 and 2, the upper *a* is divided at the heel, and one border *b* of the upper at the dividing line is extended so as to overlap an extension *c* of the upper at the other side of the dividing line. The overlapping member *b* is extended further in the form of a strap *d* held in a buckle *e* of any suitable construction so as to permit adjustment of the degree of pressure on the foot. The overlapping member *b* may be secured to the upper at the outer side of the shoe, by any other suitable means, e. g. by a button and button-hole or loop or the like.

Each side of the upper is lasted in or otherwise attached to the sole as far as the middle *f* of the heel and is there left loose to allow the entrance of the foot. It however extends beyond such middle position.

If desired moreover, the said extension or strap *f* of any substantial length may pass through a loop secured to the outer side of the shoe so as to prevent the extension or strap from flapping about when the shoe is not in use, and thus causing inconvenience. This loop may be arranged vertically or at an incline as desired.

Shoes made according to my invention may be advantageously used for dancing and gymnastics or sport generally, since the shoe is held well on the foot and the muscles of the foot relieved from all strain (*a*) by the length of the vamp and (*b*) by the adjustable button or buckle. Another advantage obtained, since no stiffening is normally required, is the give or capacity of yielding thus permitted to the rear portion or counter of the shoe.

Suitable stiffening material may however be introduced into one of the parts, e. g. the inner part of the upper adjacent the dividing line. Or both of such parts may be provided with stiffening material.

In the form of my improved shoe shown in Figures 3 and 4, the flaps *b*, *c* of the upper are made so as to overlap each other also where they are lasted in, e. g. they overlap each other from *g* to *h*, where they are attached to the sole, i. e. at or near the place where the rear opening of the upper is situated, thus further assisting in preventing the entrance of moisture at the heel.

In the form shown in Figures 5 and 6, instead of the division or slit between the two flaps *b*, *c* extending down to the sole, it may only extend down to a suitable distance above the sole, preferably to a position *j* midway between the sole and the upper edge of the shoe upper as shown, i. e. at the crest of the curve of the heel, thus further ensuring that water shall not enter the interior of the boot or shoe. In the modern shoe, the back or counter is made with so strong a curve up from the heel and towards the foot, that the foot has to be forced past the obstructing top of the counter. This is obviated by my invention, see Figures 5 and 6, where the inward curve at the top is shown in Figure 5 whilst the counter can be opened as in Figure 6 to permit the easy insertion of the foot.

In Figure 7, the inner border *c'* of the upper at the dividing line is also extended and formed into a strap *k*, which may pass to the exterior either through a slit in the upper or it may extend out through the open part of the shoe as shown, such extension being either secured to the straplike extension *d'* of the outer border extending round the other side of the shoe by means of a buckle *m* mounted on one of the straps as shown, or the buckle may be secured to the vamp or upper itself. The securing means may be, e. g. a buckle or a loop or eye and a button in each case. If desired the vamp may be cut away lower at the front part of the shoes more especially in the case of ornamental shoes.

By this means, the inner lap *c'* at the rear opening is drawn up positively, the tension thereon being substantially equal to that on the outer overlapping extension *b* of the rear part of the upper.

If desired moreover, in order to ensure that water shall not enter at the joint at the heel where the shoe is required for service in places where an exceptional amount of water is liable to be encountered, a strip or tongue of india-rubber may be lasted into the sole and arranged e. g. transversely on the inside of the outer border or overlapping piece or on the outside of the inner lap, such strip being compressed when the lap or laps are drawn up and held by the securing means.

The india-rubber may also be in the form of a folded strip, a closed tube, or of other suitable form.

In Figures 8 and 9, the free end of the outer flap is forked or branched into two straps d' , d'' which are adapted to be held by means of two buckles or fasteners e' , e'' , Figure 8, or by means of a fastener n , Figure 9, adapted to hold them both. By this means the two branches or straps can be arranged at a suitable angle to each other and thus enable the leather or other material of the flap to be drawn snugly against the whole surface of the heel notwithstanding its curvature in two directions at right angles to each other.

In Figure 10, there is shown a shoe the design of which is serviceable as a golosh. Here the heel part of the upper is partly closed as in the shoe shown in Figures 5 and 6, the flaps being both provided with straps d , k as in the shoe shown in Figure 7.

In Figure 11, in order to prevent the ingress of dust or water into the interior space of the shoe, a heel closing piece o is provided formed of thin flexible and preferably watertight material, which is secured along its bottom edge p , being preferably lasted in around the curve of the heel, and secured at one vertical edge q to the flap c of the upper on the inside thereof. This piece of thin flexible material can be readily pushed down out of the way of the foot as the latter is inserted into the boot and be raised again when the foot is in position in the shoe. This piece of thin material lies inside the innermost flap when the rear flaps of the upper are fastened in their closed position when the shoe is in use. In some cases this piece o is secured along one substantially vertical edge only to the flap c as shown in Figure 11. It may however be also secured along the lower part of its other vertical edge to the flap b to such a distance as to leave room for the flap c to pass over and beyond it, the flap c being suitably shaped as desired. This flexible material may be provided with vertically or horizontally extending pleats to facilitate its collapse when required to permit the insertion of the foot into the shoe. In this case also a strip or strips of india-rubber can be provided for making a fluid-tight joint between the flexible material and the inner sides of the flaps or end parts of the sides of the upper.

Figure 12 shows another form of shoe in which the strip of flexible waterproof material o' is secured along one vertical edge q' to the outside of the flap c and along the other vertical edge r to the inside of the outer flap b in addition to being lasted into the sole along the lower edge p . This strip of flexible material is formed with substantially vertical pleats, such pleats may be arranged e. g. fanwise and so located on each side of the

heel as to register respectively with the hollows at the rear of the ankle bones or malleoli, the middle portion thereof in contact with the heel proper being preferably unpleated, more especially in the case of ordinary shoes or boots. In the case of goloshes there would be no objection to the pleating extending around the heel. By this means, the strip can be opened out backwards when the rear flaps of the upper are unfastened, so as to permit the ready introduction into or removal of the foot from the shoe.

In suitable material the pleats may be substituted by gathers.

The flexible strip above mentioned may be formed separately from the flaps of the upper at the heel, as above described, or it may be formed integrally with the inner flap. In either case it is held securely in its closed position when the outer flap or strap of the upper is fastened to the outside of the upper, e. g. at the outside of the shoe.

By my improved construction, the upper can be made of any thin soft leather or other flexible material which will fit smoothly and yieldingly around the heel, so that the risk of chafing the heel during walking which is liable to take place with stiffened heels, is reduced to a minimum or even precluded.

In Figures 13 and 14, I have shown a boot constructed according to my invention. Here the outer flap s is provided with a plurality of branches or straps d'' , d''' adapted to engage corresponding buckles e'' , e''' or other suitable fastenings on the inner flap t . Such boots may be provided with internal closing pieces or tongues such as are described with reference to Figures 11 and 12.

In a further modification, in order still further to facilitate the insertion of the foot into the shoe, the rear parts of the sides of the upper can be left free around the curved rear border of the heel e. g. they are only connected to the sole up to the points at which two tangents to the heel, which are parallel to each other and to the longitudinal axis of the shoe, touch the heel arc or curve. By this means the rear end of the upper can be completely opened to permit the easy insertion of the foot into the shoe. This form of my invention may advantageously be applied to sandals, goloshes, gymnastic shoes and the like.

What I claim is:—

1. A shoe, slipper, boot or the like, which comprises an upper each side of which is lasted into the sole to a position at the rear of the heel and is then left free with flap parts on the rear of the upper which extend beyond the area of pressure upon the heel of the wearer and overlap one another, and means for securing said overlapping flap parts in position on the foot.

2. A shoe, slipper, boot or the like, which comprises an upper each side of which is

lasted into the sole to a position at the rear of the heel, integral flap parts of the upper on each side of the shoe extending beyond the parts of the upper lasted to the sole to extend around the heel of the wearer beyond the area of pressure thereon and adapted to overlap one another, an extension of one flap formed into a strap, and a fastening attached to the shoe, slipper, boot or the like and adapted to engage said strap.

3. A shoe, slipper, boot or the like, which comprises an upper each side of which is lasted into the sole to a position at the rear of the heel where it is divided, integral flap parts of each side of the shoe extending beyond the parts of the upper lasted to the sole to extend around the heel of the wearer beyond the area of pressure thereon and adapted to overlap one another, fastening means attached to the shoe, slipper, boot or the like, and an extended portion of one flap cooperating with said fastening means to retain the flap parts in position around the heel of the foot.

4. A shoe, slipper, boot, or the like which comprises an upper divided substantially at the counter, flap parts forming extensions of the upper on each side of the division being extended so as to overlap one another around the heel beyond the area of pressure between the heel and the counter, means for securing said extended parts in position on the foot, and a heel closing piece formed of thin, flexible and waterproof material lasted in at its bottom edge around the curve of the heel and secured to the divided parts of the upper.

5. A shoe, slipper, boot or the like comprising a sole, an upper divided at the counter, free extensions of the upper on both sides of the division extending around the heel beyond the area of pressure between the heel and the counter so as to overlap one another, and means secured upon the upper for retaining the free extensions in position around the heel of the foot.

45 6. A shoe, slipper, boot or the like comprising a sole, an upper lasted into the sole and divided at the counter, rearward flap portions formed into free extensions of the upper on each side of the counter and adapted to overlap one another around the foot, said flap portions extending beyond the area of pressure between the counter and the heel, and means for retaining the overlapping flap portions of the upper in position around the heel of the foot.

7. A shoe, slipper, boot or the like, comprising a sole, an upper divided at the center of the counter, free parts of the upper extending on each side of the upper beyond the area of pressure between the heel of the foot and the counter, and means for securing the free parts of the upper in overlapping position around the heel.

60 8. A shoe, slipper, boot or the like, comprising a sole, an upper lasted to the sole and

divided at the center of the counter, finger pieces formed by free extensions on each side of the upper at the division of the counter, said finger pieces extending around the heel of the foot beyond the area of pressure between the heel and the counter and adapted to overlap one another, and means for securing the free parts of the upper in position on the foot.

9. A shoe, slipper, boot or the like which comprises an upper divided substantially at the counter, flap parts forming extensions of the upper on each side of the division being extended so as to overlap one another around the heel beyond the area of pressure between the heel and the counter, means for securing said extended parts in position on the foot, and a heel closing piece formed of thin, flexible and waterproof material united to the divided parts of the upper.

10. A shoe, slipper, boot or the like which comprises an upper divided substantially at the counter, flap parts forming extensions of the upper on each side of the division being extended so as to overlap one another around the heel beyond the area of pressure between the heel and the counter, means for securing said extended parts in position on the foot, and a heel closing piece formed of thin, flexible and waterproof material lasted in at its bottom part to the sole and united to the divided parts of the upper.

PAMELA BULLOCK.
